US0D1001134S

(12) **United States Design Patent** (10) **Patent No.:** **US D1,001,134 S**
(45) **Date of Patent:** ** *Oct. 10, 2023

(54) **DISPLAY FOR A PORTABLE DISPLAY DEVICE**

(75) Inventors: **Jody Akana**, San Francisco, CA (US); **Bartley K. Andre**, Menlo Park, CA (US); **Jeremy Bataillou**, San Francisco, CA (US); **Eugene Cheung**, San Francisco, CA (US); **Sean Stewart Corbin**, San Jose, CA (US); **Daniel J. Coster**, San Francisco, CA (US); **Danielle De Iuliis**, San Francisco, CA (US); **Evans Hankey**, San Francisco, CA (US); **Julian Hoenig**, San Francisco, CA (US); **Richard P. Howarth**, Cupertino, CA (US); **Jonathan P. Ive**, San Francisco, CA (US); **Duncan Robert Kerr**, San Francisco, CA (US); **Stephen McClure**, San Francisco, CA (US); **Shin Nishibori**, Portola Valley, CA (US); **Benjamin Mark Rappoport**, San Francisco, CA (US); **Matthew Dean Rohrbach**, San Francisco, CA (US); **Peter Russell-Clarke**, San Francisco, CA (US); **Christopher J. Stringer**, Woodside, CA (US); **Eugene Antony Whang**, San Francisco, CA (US); **Rico Zorkendorfer**, San Francisco, CA (US)

(73) Assignee: **Apple Inc.**, Cupertino, CA (US)

(*) Notice: This patent is subject to a terminal disclaimer.

(**) Term: **14 Years**

(21) Appl. No.: **29/385,792**

(22) Filed: **Feb. 18, 2011**

(51) LOC (14) Cl. **14-03**
